CLAIM

The ornamental design for a user interface trim frame and user interface assembly, as shown and described.

DESCRIPTION

FIG. 1 is a front isometric view of the present invention shown with environmental structure;

FIG. 2 is a detail front isometric view of the invention of FIG. 1;

FIG. 3 is a front elevation view of the invention of FIG. 1; FIG. 4 is a top plan view of the invention of FIG. 1, the bottom plan view being a mirror image thereof;

FIG. 5 is a cross section view of the invention of FIG. 1 taken along line 5-5 of FIG. 3;

FIG. 6 is a right side elevation view of the invention of FIG. 1, the left side elevation view being a mirror image thereof; and,

FIG. 7 is a cross section view of the invention of FIG. 1 taken along line 7-7 of FIG. 3.

The broken dash lines and broken dash hatching in the figures represent non-claimed subject matter. Neither the broken dash line portions nor the broken dash lines themselves forms any part of the claimed invention.

1 Claim, 4 Drawing Sheets
